UNITED STATES PATENT OFFICE.

DUDLEY T. FISHER, OF COLUMBUS, OHIO, ASSIGNOR TO THE JEFFREY MANUFACTURING COMPANY, OF COLUMBUS, OHIO, A CORPORATION OF OHIO.

COAL-MINING APPARATUS.

1,321,427.

Specification of Letters Patent. Patented Nov. 11, 1919.

Application filed August 28, 1914. Serial No. 859,077.

To all whom it may concern:

Be it known that I, DUDLEY T. FISHER, a citizen of the United States, residing at Columbus, in the county of Franklin and State 5 of Ohio, have invented certain new and useful Improvements in Coal-Mining Apparatus, of which the following is a specification, reference being had therein to the accompanying drawings.

10 This invention relates to improvements in machines for mining coal and loading it for transportation from the mine.

The principal object is to provide a machine having means for forming a plurality 15 of parallel vertical kerfs in the face of the coal, means for breaking down the coal between these kerfs and means for gathering the said coal and loading it into conveniently placed cars adapted to transport it 20 from the mine. Machines embodying my invention are capable of wide variation and may be adapted to use with any of the well known systems of mining, such as the long wall system, or the room and pillar system, 25 or modifications of them, and it is not the intention that any thing herein contained shall limit use of the machines.

The preferred construction, adapted to work in a room having a semicircular working face, is fully described in the following 30 specification and illustrated in the accompanying drawings of which—

Figure 1 is a general plan view of the machine.

35 Fig. 2 is a side elevation, partly in cross-section of the machine shown in Fig. 1.

Fig. 3 is an enlarged plan view of the mining elements of the machine.

40 Fig. 4 is a side elevation of the cutting mechanism and the driving connections therefor.

Fig. 5 is an end elevation of the breaking down mechanism.

45 Fig. 6 is a side elevation of the breaking down mechanism.

Fig. 7 is a section on the line 7—7 of Fig. 3.

Fig. 8 is a section on the line 8—8 of Fig. 2.

50 Fig. 9 is a fragmentary plan view showing the driving connections of the loading conveyer and of the feed mechanism.

55 In the embodiment of my invention herein disclosed are three elements, the cutting mechanism, the breaking down mechanism

and the loading mechanism, all of which are combined to form a complete machine.

The cutting mechanism comprises a cutter head of the well known chain type in which a cutter chain 1, having renewable 60 bits 2 adapted to cut the coal, travels in suitable guides formed on the edges of a cutter frame 3. The frame 3 is mounted for limited oscillation in a vertical plane about the head shaft 4 to form vertical kerfs 65 in the face of the coal. The cutter frame 3 is supported on journal bearings 5 rotatable on the shaft 4 on either side of the head sprocket wheel 6 by which the chain 1 is driven. Power is derived from the motor 9 70 through the head shaft 4 and the bevel gears 7 and 8. The head shaft 4 is supported, preferably at a low elevation in journal bearings 10, 11 and 12 from the base plate 13, which is adapted to slide over the 75 floor of the mine and which supports the motor 9 and other parts of the mechanism as will hereinafter appear. Attached to the cutter frame 3 are upward extending arms 14 connected at their upper ends to a 80 lifting screw 15 by a pivot pin 16. The lifting screw 15 is slidable in the bearings 17 and 18 of the yoke 19 supported by bearings 20 upon the shaft 21. This shaft is journaled in bearings 22 carried by the 85 brackets 23 and 24 upstanding from the base plate 13. Screw threaded to the lifting screw 15 is a nut 25, positioned between the bearings 17 and 18, and having, formed on its periphery, spiral gear teeth to engage the 90 spiral gear 26 upon the shaft 21. The shaft 21 is driven by the bevel gear 27 meshing with a similar gear 27^a attached to the upper end of the vertical shaft 28. This shaft is 95 journaled at its upper end in a bearing 29 of the bracket 23, and at its lower end in the step bearing 30 of the floor plate 13. Mounted for free rotation upon the vertical shaft 28 are two bevel gears 31 and 32 both 100 meshing with the bevel gear 33 carried by the head shaft 4. Splined to the vertical shaft 28, between the bevel gears 31 and 32, is a jaw clutch 34 having teeth adapted to engage similar teeth on the gears 31 and 32 to 105 connect either of them with the shaft to drive it. The clutch member is controlled by the lever 34^a. The direction of rotation of the shaft 28 will depend upon which of the bevel gears is engaged. By shifting the clutch member 34 either upward or downward the 110

operator may cause the nut 25 to revolve in either direction to raise or lower the cutter head as occasion may require.

The breaking down mechanism comprises 5 a reciprocating pick tool, so mounted that its blows may be directed against any desired point of the coal, in a direction either at right angles to the face or parallel thereto. This pick mechanism may be of any of the 10 well known constructions and may be actuated by any convenient motive power, such as compressed air, internal combustion engine or some one of the many forms of electric motor. In the construction disclosed 15 herein I have provided a mechanism operated from the motor 9, but as its details form no part of the present invention I do not intend to limit myself to the construction shown.

20 The head shaft 4 extends through the bearing 12 and carries on its end a bevel gear 35 meshing with a similar gear 36 carried by the vertical shaft 37 journaled at its upper end in the bearing 38 of the bracket 39, and at its lower end in the step bearing 40 formed on the floor plate 13. Journaled upon the outer surface of the bearings 38 and 40 is a yoke 41 having a foot 42, adapted to slide on the floor plate 25 13, and a bearing 43 in which is journaled a horizontal shaft 44. Mounted for rotation 30 upon the outside of the bearing 43 is a member 45 having a bearing 46 in which is journaled a shaft 47 at right angles to the shaft 44. Journaled upon the outside of the bearing 46 is a member 48 having a bearing 49 in which is journaled a crank shaft 50 at right angles to the shaft 47. The bevel gears 36, 51, 52, 53, 54, and 55 attached to 35 the shafts 37, 44, 47 and 50 form a train to drive the crank shaft 50 from the head shaft 4. Journaled upon the outside of the bearing 49 is a yoke 56 having extending arms 57 and 58 at the ends of which are 40 guide blocks 59 and 60 in which slide the rods 61 of the pick frame. Fixed to the rear end of the rods 61 is a cross member 62 having a wrist pin 63 connected by the connecting rod 64 with the crank 65 attached to the crank shaft 50. Fixed to the 45 rods 61 forward of the slide block 60 is a cross member 66 having an aperture 67 through which the pick tool 68 is slidable. A nut 69 attached to the pick tool 68 prevents its 50 slipping forward out of the aperture 67. Fixed to the pick tool 68 is a cross member 70 slidable on the rods 61. A coil spring 71 is interposed between the cross members 66 and 70 to drive the pick tool against the coal 55 as the pick frame reciprocates, and to cushion the machine against destructive shocks when the picks strike the coal. A handle 72 attached to the yoke 56 affords 60 convenient means of directing the pick 65 against any desired point of the coal face

and especially against the lateral faces formed by the cutting of the vertical kerfs. Since the pick is mounted for horizontal movement both about the axis of shaft 37 and the axis of shaft 47 and for vertical 70 movement both about the axis of shaft 44 and the axis of shaft 47, it is possible to direct the stroke of the tool in any direction and to attack either the front faces or the lateral faces of the coal most effectively. 75

The machine is provided with a pivoting device by which it is limited to movement in a circular path. This pivoting device comprises a pivot post 73 securely held in position on the center line of the mine working. To the post is connected for pivotal movement a radius frame 74 rigidly fastened to the floor plate 13 of the mining machine. Resting on the rails 75 of the mine track are wheels 76 supporting the truck platform 77 85 from which rises the pivot post 73, the upper part of which is screw threaded to coöperate with the hand wheel nut 78. The nut engages the cap 79 to force the latter into contact with the roof of the mine, thereby holding the post 73 against lateral displacement. Brake shoes 80 are suspended from the truck platform 77 by links 81 and are forced in contact with the wheels 76 by the double acting hand wheel nut 82 screw 95 threaded to the struts 83. Movement along the rails is thereby resisted.

The radius frame 74 is composed of angle bars 84 connected together by suitable cross members to form a rigid structure. At their 100 inner ends the angle bars 84 are attached to a casting 85 bolted to the floor plate 13, and at their outer ends to a casting 86 on which is formed a sleeve 87 journaled upon the post 73 and vertically supported by a 105 shoulder 89 thereof. The angle bars 84 are arranged to form guides for the endless chain 90 of the gathering conveyer. The chain 90 carries laterally projecting scrapers 91 which travel along the trough 92 to propel the coal therethrough. The bottom plate of the trough 92 is bent upward and outward to form flaring sides 93 to confine the coal to the conveyer while in transit. At the outer end of the conveyer the chain 90 runs 115 over a sprocket wheel 93 journaled on the outer surface of the sleeve 87, concentric with the post 73. The sprocket wheel 93 is concentrically attached to the bevel gear wheel 94 which meshes with the bevel pinion 95 carried by the longitudinal shaft 96. The shaft is driven through the spur gear 97 and the pinion 98 from the motor 99 mounted upon the strut frame. The shaft 96 is journaled at its outer end in a bearing 100 formed on the casting 86 and at its inner end in a bearing 101 attached to the frame of the motor. At the inner end of the conveyer the chain 90 runs over a sprocket wheel 102 journaled on a vertical pin 103 in 130

the foot casting 104. The casting is secured to the floor plate 13 by suitable bolts 105. The holes through the casting 104 for the passage of the bolts 105 are slotted to admit 5 of longitudinal adjustment to regulate the tension of the chain 90. Means for such adjustment is provided in the adjusting screw 106 which is threaded into the foot casting 104 and bears at its other end in an aperture 10 of the casting 85. A closed conduit 107 is provided along the rear side of the strut frame for the return strand of the chain and flights to protect the operator from accidental contact therewith. The foot casting 15 104 is so positioned with reference to the other parts of the machine that the scraper 91 will reach the extreme inner edge of the floor plate 13 to gather any coal which may fall thereon.

20 The loading conveyer is of the well known metallic apron type, comprising two similar endless chains 108 traveling over sprocket wheels 109 mounted upon the transverse idle head shaft 110 and over 25 other sprocket wheels 111 keyed to the transverse foot shaft 112, and connected together at every link by transverse overlapping plates or flights 113 so formed at their edges as to allow free movement 30 around the sprocket wheels and maintain sufficiently close articulation to prevent material from falling between adjacent flights. The chains are of the well known roller type, each link having a roller adapted to 35 travel over suitable trackage surfaces to carry the weight of the chain and flights and of the material carried thereby.

The supporting frame work upon which this apron is mounted consists of longitudinal 40 angle bars 114 and 115 upon which the chain rollers travel, connected together by suitable transverse angle bars 116 and by substantially perpendicular angle bars 117 and 118. The angle bars 118 are secured 45 to the truck platform 77 in any preferred manner, such as bolts or rivets. Suitable side plates 119 are attached to the frame angles to confine the coal to the conveyer, and these plates are extended at the inner 50 end to form a hopper 120 to receive the coal as it is discharged from the gathering conveyer. The head shaft 110 is journaled in take up journal boxes 121 supported on plates 122 attached to the longitudinal angle bars, to regulate the tension of the chains 108 by means of the screws 123 in the manner common to such journal boxes. The foot shaft 112 is journaled in pillow blocks 124 attached to the truck platform 77. 55 Mounted for rotation upon the foot shaft 112 is a spur gear 125 connectible thereto by a jaw clutch 126 operated by the lever 126a. The gear 125 is driven through the pinion 127, the shaft 128, the gear 129 and 60 pinion 130 from the motor 131 to propel the

conveyer. The shaft 128 is journaled in bearings 132 of the truck platform 77 and carries a sprocket wheel 133 connected by the chain 134 to the sprocket wheel 135. The sprocket wheel 135 is carried by the 70 feed shaft 136 journaled in bearings 137 and 138 of the truck platform. Freely mounted on the feed shaft 136 is a feed drum 139 to which is attached a feed rope 140 adapted to be wound thereon. A friction clutch 141 is provided by which the drum 139 may be connected to the shaft 136 to cause it to rotate to wind the rope. Suitable guide sheaves 142, 143 and 144 are provided in convenient positions upon the truck 80 platform to guide the rope 140 in directions convenient for handling the machine.

75 The operation of the machine is as follows. The pivot post 73 being set on the center line of the working at a distance 85 from the face equal to the length of the radius frame, less the desired depth of cut, with the mining elements at the extreme right hand side of the room, the cutter head frame 3 will be elevated. A jack such as 90 is commonly used with mining machines, to which has been attached a snatch block, is set in any convenient position to the left of the machine. The feed rope 140 is 95 drawn out from the drum 139 passed around the snatch block and its end attached to the hook 146 fixed on the floor plate 13. The feed rope will then be wound up, causing the base plate to slide toward the left, until the cutter head reaches the position desired 100 for the first cut, whereupon the feeding is stopped. The motor 9 is then started and the clutch 34 manipulated to lower the cutter head, cutting a kerf in the face of the coal extending to the floor of the mine. The 105 clutch 34 is then reversed to lift the cutter head clear of the kerf, and the rope feed is started to move the machine over to the position for the next cut. As soon as the machine has advanced a sufficient distance the 110 pick is brought into action and the coal between the kerfs is broken down to fall onto the floor plate 13 and be gathered by the flights of the gathering conveyer and carried through the trough 92 of the hopper 115 115 120 of the loading conveyer. The loading conveyer discharges it into the car 147 conveniently placed on the tracks 75 for transport from the mine.

120 As the coal will readily break along the lines of natural cleavage, the face can be kept substantially vertical allowing sufficient clearance for the cutter head when in its most elevated position, to be moved along the face without moving the other parts of 125 the machine away from the face. The attainment of this result is facilitated by the arrangement of the head shaft 4 close to the floor, for this makes it possible for the swinging cutter arm to cut the kerf at 130

practically full depth well down to the floor level so that the coal at the lower part of the seam can be effectively loosened by the pick while the coal at the higher levels, 5 where the kerf is not cut so deeply, tends to loosen under its own weight.

When the coal has been mined across the entire face, the jack will be set to the right of the machine and the mining elements 10 pulled over to the place of beginning. The post 73 will then be advanced an amount equal to the desired depth of cut and the operation repeated.

What I claim is:

- 15 1. In apparatus of the character set forth, the combination of a frame adapted to travel along a coal face, an elongated cutter arm carried by the frame and having one end pivotally mounted on a horizontal axis 20 disposed relatively close to the mine floor, an endless cutter chain mounted to travel around the periphery of the cutter arm, means for swinging the cutter arm upward and downward around the aforesaid axis to 25 cut vertical kerfs in the coal transverse to the face thereof, and an impact breaking device mounted on the frame and arranged to strike the lateral faces formed by the cutting of the aforesaid vertical kerfs.
- 30 2. In apparatus of the character set forth, the combination of a frame, means for guiding said frame in a path parallel to an arcuate coal face, an elongated cutter arm carried by the frame and having one 35 end pivotally mounted on a horizontal axis disposed relatively close to the mine floor, an endless cutter chain mounted to travel around the periphery of the cutter arm, means for swinging the cutter arm upward, 40 and downward around the aforesaid axis to cut vertical kerfs in the coal transverse to the face thereof, and an impact breaking device mounted on the frame and arranged to strike the lateral faces formed by the 45 cutting of the aforesaid vertical kerfs.
- 50 3. In apparatus of the character set forth, the combination of a frame, means for guiding said frame in a path parallel to an arcuate coal face, an elongated cutter arm carried by the frame and having one end 55 pivotally mounted on a horizontal axis disposed relatively close to the floor of the mine, an endless cutter chain mounted to travel around the periphery of the cutter arm, means for swinging the cutter arm upward and downward around the aforesaid axis to cut vertical kerfs in the coal transverse to the face thereof, and an impact 60 breaker carried by the frame and adapted to move independently of the vertical kerf cutting devices and to strike the lateral faces formed by the cutting of the aforesaid vertical kerfs.
- 65 4. In apparatus of the character set forth, the combination of a frame adapted

to travel along a coal face, cutter mechanism mounted on said frame and adapted to cut vertical kerfs in the coal transverse to the face thereof, and an impact breaking device mounted on the frame to swing horizontally for the purpose of effectively attacking either the front face of the coal between the vertical kerfs or the lateral faces formed by said kerfs, and to move vertically for the purpose of effectively reaching both 75 the upper and lower parts of the coal.

5. The combination in a coal cutting and breaking-down machine, of a main frame adapted to be moved parallel with a coal face, a kerf cutter mounted on said frame 80 for cutting kerfs in the coal at an angle to the front face thereof in different places along the face of the coal according to the position of the machine, a reciprocable breaking down device mounted on said main 85 frame and adjustable and operable independent of the kerf cutter, a bearing adjustable on said frame and having means for guiding the sliding of said breaking-down device, mechanism for actuating the 90 latter, and a conveyer on the frame for engaging and removing the broken-down coal.

6. The combination in a coal cutting and breaking-down machine, of a main frame adapted to be moved parallel with a coal 95 face, a kerf cutter mounted on said frame for cutting kerfs in the coal at an angle to the front face thereof in different places along the face of the coal according to the position of the machine, a reciprocable 100 breaking down device mounted on said main frame and adjustable and operable independent of the kerf cutter, a bearing for supporting and guiding the breaking-down device, said bearing being adjustable on 105 said frame to shift the axis of the breaking-down device in vertical and in horizontal planes, and mechanism for actuating the breaking-down device.

7. In apparatus of the character set forth, 110 the combination of a frame adapted to travel along a coal face, cutter mechanism mounted on said frame and adapted to cut vertical kerfs in the coal transverse to the face thereof, a reciprocable coal breaking 115 device mounted on the frame, and means for adjusting said breaking device horizontally and vertically for the purpose of attacking the front or side faces of the coal, at different heights as may be required, and 120 mechanism for actuating said breaking device.

8. The combination in a coal cutting and breaking-down machine, of a main frame adapted to be moved parallel with a coal 125 face, a kerf cutter mounted on said frame for cutting a kerf in the coal at an angle to the front face thereof, a reciprocable breaking down device mounted on said main frame above said kerf cutter and adjustable 130

and operable independent of the kerf cutter, a bearing adjustable on said frame and having means for guiding the sliding of said breaking-down device, mechanism for actuating the latter, and a conveyer on the frame for engaging and removing the broken-down coal.

9. The combination in a coal cutting and breaking down machine, of a main frame adapted to be moved parallel with a coal face, a kerf cutter mounted on said frame for cutting kerfs in the coal at an angle to the direction of movement of said frame in different places along the face of the coal according to the position of the machine, a reciprocable breaking down device mounted on a universal pivotal support, and a support for said pivotal support adjustable on said main frame and adjustable relative to said kerf cutter.

10. The combination in a coal cutting and breaking down machine, of a main frame adapted to be moved parallel to a coal face, a kerf cutter mounted on said frame for cutting kerfs in the coal at an angle to the direction of movement of said frame in different places along the face of the coal according to the position of the machine, a reciprocable breaking down device mounted on a universal pivotal support, and a support for said pivotal support adjustable on said main frame to shift said breaking down device relative to said kerf cutter. 25 30

In testimony whereof, I affix my signature, in presence of two witnesses.

DUDLEY T. FISHER.
